ROUND HEEL IRON

Abe O. Samuels, Rochester, N. Y., assignor to
Samson-United Corporation, Rochester, N. Y.

Application November 14, 1935, Serial No. 49,837

15 Claims. (Cl. 219—25)

This invention relates to electrically heated irons for ironing fabrics and pressing garments and has for its object to provide such an iron with a heated round heel for the purpose of increasing the efficiency and usefulness of the iron.

This and other objects of this invention will become more readily apparent from the detailed description thereof which follows, reference being had to the accompanying drawing in which

Figure 1 is a side elevation of an electrically heated iron embodying my invention.

Figure 2 is a top plan view of the sole plate of the iron with the heating coil embedded therein.

Figure 3 is a detail sectional view of the sole plate taken on the line 3x—3x of Figure 2.

In the several figures of the drawing like reference numerals indicate like parts.

20 The electrically heated iron forming the subject matter of my present invention has been found to increase the efficiency and usefulness of such an iron. Heretofore no special attention was given to the heating of the heel of an iron with the result that while the body and front of the iron was heated for the efficient operation and use of the iron, the heel portion was neglected and no special use could be made of it. Practically all irons now on the market 25 have a sharply cornered heel and the heating unit carried by the sole plate is so positioned with relation to the heel that heat is very poorly transmitted to the edge thereof. If therefore the iron is tilted to rest on the heel, but a small 30 portion of the heat generated at the heel end of the iron is transmitted to the fabric for ironing purposes.

In the use of an electrically heated iron it has been found advantageous to tilt the iron and use 35 the heel of the iron for ironing purposes and of course this made it necessary to round the heel to prevent tearing of the fabric as the heel is moved over it. Rounding the heel however did not solve the problem of making the heel an 40 efficient medium for special ironing purposes because the heating element could not transmit sufficient heat to the heel to make its use effective. In my present invention this drawback has been entirely eliminated by the use of a round 45 heel in combination with a heating coil which is located in the heel plate in predetermined relation to the entire curved surface of the heel so as to quickly and efficiently heat the round heel and what is most important maintain the necessary heat during the ironing process.

As illustrated in the drawing the iron is made up of the sole plate 1, the top of which is covered by the shell 2 with the handle 3 clamped to the top of the shell and anchored to the sole plate by means of the anchoring bolt 4. The form of sole plate illustrated in the drawing is cast with a pocket in the form of the channel 5 therein. The outer walls of this channel are substantially parallel to the sides and the heel end of the sole plate and are suitably spaced therefrom. The 10 channel is filled with a suitable cement and in the cement is embedded the heating coil 6 which is located and distributed so as to efficiently transmit and maintain the proper heat over the entire sole plate. The efficient distribution of the heat 15 of the iron has heretofore been accomplished with regard to the forward and the body portion of the iron but this has never been attained for the heel of the sole plate. As long as the heel of an iron was not used for special ironing this 20 course was not apparent in the use of the iron. In the development of my present invention of a round heel for the sole plate for special ironing purposes however, I have found it most important to so locate a portion of the heating 25 coil 6 that not only the entire curved surface of the heel is quickly heated to the proper temperature but that this heat is constantly maintained while the heel is being used for ironing purposes, 30 and both sole and heel portions uniformly heated. 30

It is a well known fact that any portion of a heated body which is brought in contact with a moist surface rapidly loses heat until the moisture is evaporated. This absorption of heat cools the heated body unless sufficient reserve heat is 35 produced by the heating coil and transmitted to the portion of the body in contact with the moist surface. To make this possible for the heel of the sole plate of an electrically heated iron I have therefore embedded or otherwise mounted 40 the heating coil portion in the rear of the sole plate in close proximity to the heel and have rounded the heel substantially concentric to the heating coil so that any part of the curved surface of the round heel will have a constant and 45 equal amount of heat transmitted to it from the heating coil. This is illustrated in Figure 3 in which the heating coil portion 6A which extends parallel to the heel of the iron, is substantially 50 concentric to the surface of the rounded heel 7 and in close proximity thereto.

As shown particularly in Figures 2 and 3, the heel of the iron is transverse of the longitudinal axis of the iron, and has a curved surface which is formed by translating a substantially linear 55

element through successive positions which are parallel to each other, such as an arc of a cylindrical surface. As shown, the heel portion 6—A of the heating element is positioned with its axis 5 substantially parallel to the curved heel surface, that is, to the successive positions of the linear element generating the heel surface, or the axis of the cylindrical surface.

From the foregoing description of the construction of my improved device, the operation thereof and the method of applying the same to use will be readily understood. It will be seen that I have provided a simple, inexpensive and efficient means for carrying out the objects of 10 the invention and while I have particularly described the elements best adapted to perform the functions set forth, it is obvious that various changes in form, proportion and in the minor details of construction may be resorted to, without departing from the spirit or sacrificing any 15 of the principles of the invention.

I claim:

1. In an electrically heated iron having a heavy cast sole plate, a rounded heel provided on said sole plate and a heating coil carried by said sole plate in close proximity thereto and substantially concentric thereto.

2. In an electrically heated iron, a heavy sole plate having a forward toe portion and a rear heel portion, said heel portion being substantially straight transversely of the longitudinal axis of said iron, an electrical heating element mounted in said sole plate and having a portion positioned in the heel portion of said sole plate substantially 30 transverse of the longitudinal axis of said iron, said heel portion of said sole plate extending downwardly with a rounded heel surface substantially parallel to and curved about said heel portion of said heating element as a center of 35 curvature for keeping all portions of said rounded heel surface substantially uniformly heated at all times.

3. In an electrically heated iron, a heavy sole plate having a forward toe portion and a rear heel portion, the surface of said heel portion being formed by translating a substantially linear generating element along a curve generating through successive positions which are substantially parallel to each other and are transverse of the longitudinal axis of said iron, and an electrical heating element mounted in said sole plate and having a heel portion thereof positioned in the heel portion of said sole plate close to said heel surface and transversely of the longitudinal axis of 45 said iron, said heel portion of said heating element having a substantially straight axis which is substantially parallel to the successive positions 50 of the generating element of said heel surface and which passes substantially through the center of curvature of said generating curve, whereby said heel surface is substantially uniformly heated at all times.

4. In an electrically heated iron, a heavy sole plate having a forward toe portion and a rear heel portion, the surface of said heel portion being substantially an arc of a cylindrical surface whose axis is transverse of the longitudinal axis of said iron, and an electrical heating element mounted 55 in said sole plate and having a heel portion thereof positioned in the heel portion of said sole plate close to said heel surface and transversely of the longitudinal axis of said iron, said heel portion of said heating element having a substantially straight axis which is substantially 60 coincident with the axis of said cylindrical sur-

face, whereby said heel surface is substantially uniformly heated at all times.

5. In an electrically heated iron, a heavy sole plate having a forward toe portion and a downwardly rounded rear heel portion, an electrical heating element carried by said sole plate and having a heel portion thereof carried by said rounded heel portion of said sole plate in close proximity to the surface of said rounded heel portion of said sole plate, said heel portions of said sole plate and of said heating element being so mounted and arranged that the heat-conducting paths diverging from the heel portion of said heating element to different points on the surface of the heel portion of said sole plate have substantially equal radial lengths.

6. In an electrically heated iron, a heavy sole plate having a forward toe portion and a downwardly rounded rear heel portion, an electrical heating element carried by said sole plate and having a substantially linear heel portion thereof carried by the heel portion of said sole plate, the outer surface of the heel portion of said sole plate being curved about said heel portion of said heating element as a center of curvature for keeping all portions of the surface of said rounded heel portion substantially uniformly heated at all times.

7. In an electrically heated iron, a heavy sole plate having a forward toe portion and an outwardly downwardly rounded heel portion, the heel portion of said sole plate being provided adjacent its edge with a channel having a lower rounded heel surface adjacent said rounded heel portion of said sole plate, an electrical heating element mounted in said sole plate and having a heel portion thereof mounted in said channel in said heel portion of said sole plate, and insulating material in said channel for embedding said heel portion of said heating element therein, the rounded heel surface of said channel being substantially parallel to the outward rounded heel surface of said sole plate, said rounded heel surface of said channel and the outward rounded heel surface of said sole plate being curved about 40 said heel portion of said heating element as a center of curvature.

8. In an electrically heated iron, a heavy sole plate having a forward toe portion and an outwardly downwardly rounded heel portion, the heel portion of said sole plate being provided adjacent its edge with a channel having a lower rounded heel surface adjacent said rounded heel portion of said sole plate, an electrical heating element mounted in said sole plate and having a heel portion thereof mounted in said channel in said heel portion of said sole plate, and insulating material in said channel for embedding said heel portion of said heating element therein, said heel portion of said heating element and said heel portion of said sole plate and said rounded heel surface of said channel being so constructed and arranged that the heat conducting paths between the rounded heel surface of said channel and the outward rounded heel surface of said sole plate traversed by heat rays divergently radiated from said heel portion of said heating element have substantially equal lengths.

9. In an electrically heated iron, a heavy sole plate having a forward toe portion and an outwardly downwardly rounded heel portion, the heel portion of said sole plate being provided adjacent its edge with a channel having a lower rounded heel surface adjacent said rounded heel portion of said sole plate, an electrical heating 70 element mounted in said sole plate and having a heel portion thereof mounted in said channel in said heel portion of said sole plate, and insulating material in said channel for embedding said heel portion of said heating element therein, said heel portion of said heating element and said heel portion of said sole plate and said rounded heel surface of said channel being so constructed and arranged that the heat conducting paths between the rounded heel surface of said channel and the outward rounded heel surface of said sole plate traversed by heat rays divergently radiated from said heel portion of said heating element have substantially equal lengths.

element mounted in said sole plate and having a heel portion thereof mounted in said channel in said heel portion of said sole plate, and insulating material in said channel for embedding 5 said heel portion of said heating element therein, said heel portion of said heating element and said heel portion of said sole plate and said rounded heel surface of said channel being so constructed and arranged that the diverging 10 heat-conducting paths from said heel portion of said heating element to the outward rounded heel surface of said sole plate have substantially equal lengths.

10. In an electrically heated iron, a heavy sole plate having a forward toe portion and an outwardly downwardly rounded heel portion, the heel portion of said sole plate being provided adjacent its edge with a channel having a lower rounded heel surface adjacent said rounded heel 15 portion of said sole plate, an electrical heating element mounted in said sole plate and having a heel portion thereof mounted in said channel in said heel portion of said sole plate, said heel portion of said heating element having a cross-sectional contour substantially symmetrical about a center of symmetry, and insulating material in said channel for embedding said heel portion of said heating element therein, said outward surface of said rounded heel portion of said 20 sole plate being substantially symmetrical about the center of symmetry of said heating element and substantially parallel to the contour of said heating element whereby all points of said outward rounded heel surface of said sole plate are 25 substantially equally heated.

11. In an electrically heated iron, a heavy sole plate having a forward toe portion and an outwardly downwardly rounded heel portion, the heel portion of said sole plate being provided 30 adjacent its edge with a channel having a lower rounded heel surface adjacent said rounded heel portion of said sole plate, an electrical heating element mounted in said sole plate and having a heel portion thereof mounted in said channel in said heel portion of said sole plate, said heel portion of said heating element having a cross-sectional contour substantially symmetrical about a center of symmetry, and insulating material in said channel for embedding said heel portion 35 of said heating element therein, said outward surface of said rounded heel portion of said sole plate and said rounded heel surface of said channel being substantially symmetrical about the center of symmetry of said heating element and substantially parallel to the contour of said heating element whereby all points of said outward rounded heel surface of said sole plate are substantially equally heated.

12. In an electrically heated iron, a heavy sole

plate having a forward toe portion and a downwardly rounded rear heel portion, an electrical heating element carried by said sole plate and having a substantially filar heel portion thereof carried by the heel portion of said sole plate, the cross-sectional contour of the outer surface of the heel portion of said sole plate being substantially circular about a point in said heel portion of said element as a center.

13. In an electrically heated iron, a heavy sole 10 plate having a forward toe portion and an outwardly downwardly substantially circularly rounded heel portion, the heel portion of said sole plate being provided adjacent its edge with a channel having a lower substantially circularly rounded heel surface adjacent said rounded heel portion of said sole plate, an electrical heating element mounted in said sole plate and having a heel portion thereof mounted in said channel in said heel portion of said sole plate, the outer surface of said circularly rounded heel portion of said sole plate and said circularly rounded heel surface of said channel substantially having a common center in said heel portion of said 15 heating element.

14. In an electrically heated iron, a heavy sole plate having a forward toe portion and an outwardly downwardly substantially circularly rounded heel portion, the heel portion of said sole plate being provided adjacent its edge with a channel having a lower substantially circularly rounded heel surface adjacent said rounded heel portion of said sole plate, and an electrical heating element of substantially circular cross-section mounted in said sole plate and having a heel portion thereof mounted in said channel in said heel portion of said sole plate, the outer surface of said circularly rounded heel portion of said sole plate and the circumference of said heel portion of said heating element being 20 substantially concentric.

15. In an electrically heated iron, a heavy sole plate having a forward toe portion and an outwardly downwardly substantially circularly rounded heel portion, the heel portion of said sole plate being provided adjacent its edge with a channel having a lower substantially circularly rounded heel surface adjacent said rounded heel portion of said sole plate, and an electrical heating element of substantially circular cross-section mounted in said sole plate and having a heel portion thereof mounted in said channel in said heel portion of said sole plate, the outer surface of said circularly rounded heel portion of said sole plate and said circularly rounded heel surface of said channel and the circumference of said heel portion of said heating element being 25 substantially concentric.
